CLAIM

The ornamental design for a truck bed cap, as shown and described.

DESCRIPTION

FIG. 1 is a rear perspective view of a truck bed cap with the rear window area, side windows, the rear lip of the truck bed cap, and high mount brake light recess being outlined in phantom lines, and the truck bed cap being coupled to an exemplary truck shown in phantom lines;

FIG. 2 is a left elevational view of the truck bed cap in FIG. 1, the right elevational view being a mirror image thereof, with the rear window area, side windows, and the rear lip of the truck bed cap being in phantom lines;

FIG. 3 is a rear elevational view of the truck bed cap in FIG. 1 with the rear window area, side windows, the rear lip of the truck bed cap, and the high mount brake light recess being in phantom lines;

FIG. 4 is a front elevational view of the truck bed cap in FIG. 1, illustrating the external outline thereof, with the internal outline and high mount brake light recess being in phantom lines;

FIG. 5 is a top plan view of the truck bed cap in FIG. 1 with the rear window area, side windows, the rear lip of the truck bed cap, and the high mount brake light recess being in phantom lines; and,

FIG. 6 is a bottom plan view of the truck bed cap in FIG. 1, illustrating the external outline thereof, with the internal outline being in phantom lines both with the rear portion of the truck bed cap being shown in phantom lines.

The broken phantom lines depict unclaimed subject matter only and form no part of the claimed design.
